LANGDON C. KELLOGG, OF WESTFIELD, MASSACHUSETTS.

MOP.

Application filed July 17, 1926. Serial No. 123,110.

This invention relates to improvements in mops of the type in which a mass of wool or other fibrous yarn like material is suitably secured to the head portion of the 55 mop by means of a pair of wires that are twisted together for rigidly and firmly retaining the wool fibres in place.

An object of the present invention is to provide a mop construction in which the 60 handle is rotatably connected to the head portion thereof in order that it may be rotated or turned, through a complete circle of 360° and in either direction, whereby when the mop is used for cleaning, either a 65 wall or floor the head will automatically rotate or turn relative to the position of the handle. Means is provided for rigidly clamping the handle to the head portion of the mop, if desired.

20 Broadly, the head portion comprises a pair of wires which when they are twisted together firmly retain the strands of yarn which are located between the wires. A portion of the twisted wires is bent to form a 70 straight portion for pivotally attaching the handle. The ends of the twisted wires are spaced or separated a sufficient distance to permit the handle to pass through the space 75 between the ends when either the handle or head is rotated.

Referring to the drawings:

Fig. 1 is a plan view of the complete mop showing the twisted wires of the head, the strands of yarn clamped between the wires 80 and the straight portion for attaching the handle and the spaced ends.

Fig. 2 is a sectional view on the line 2—2 of Fig. 1 showing the construction of the 85 clamp for attaching the head, and

40 Fig. 3 is a detail enlarged sectional view of the clamp construction for attaching the handle to the head.

Referring to the drawings in detail:

1 designates the handle portion; 2 and 3 90 are the oppositely disposed head clamping members located at the lower end of the handle and secured thereto by means of the rivet 4. 5 and 6 designate a pair of wires which are twisted together as shown in Figs. 1 and 2. 95 During the twisting operation the strands or fibers of yarn 7 are fed into the space

between the wires and firmly clamped or retained by the twisting operation. These strands extend at substantially equal distances on opposite sides of the wires 5 and 6 as shown to form a head of sufficient thickness. The free ends 8 and 9 of the wires are spaced from each other as indicated by the numeral 10. This space is located directly opposite the point of attachment of the handle 1, which handle is rotatably mounted on and clamped to the straight portion 11, of the twisted wires 5 and 6. Engaging this straight portion are the clamps 2 and 3 which are drawn together by means of the bolt 12 and the thumb nut 13 whereby sufficient friction may be placed on the straight wire portion 11 to permit the head to rotate or turn freely, or, if desired, firmly clamped thereto. By means of the space 10 the head 70 of the mop may be rotated in either direction through a complete circle as indicated by the dotted arrow lines 14 and 15. The different positions of the head being indicated by the lines 16 and 17.

It will be seen from this description that the head of the mop when in use, will freely turn on the pivotal connection between the handle 1 and the bearing portion 11. This is important when the mop head is moved 80 up and down on a vertical surface, as a wall, or when it is moved under a piece of furniture as the operator does not have to stoop or bend down. It is, of course, obvious that the construction may be applied in other 85 mops than dry ones for floor and wall use. Also, other material than wool fibres may be employed. The invention is not intended to be limited to the shape shown in the drawings.

What I claim is:

1. In a mop construction, the combination with a handle member, a head pivotally attached thereto, the head portion comprising a pair of twisted wires between the turns of which the cleaning elements of the mop are secured said head being formed into a loop with the ends of the twisted wire spaced from each other an intermediate portion of the twisted wire being formed to provide a bearing for the handle and located directly 100 opposite the spaced ends of the wires where-

by the head may be rotated relative to the handle and through a complete circle.

2. A mop construction comprising in combination, a looped mop head which is formed of a pair of twisted wires having strands of yarn or like fibrous material laid therein, a portion of the said wires being bent inward into the loop and connected by a straight portion to provide attaching means for the

operating handle, clamps on the handle for 10 pivotally attaching the handle to the straight portion, the head being formed with an opening opposite said straight portion to permit its being rotated past the handle and through a complete circle and in either 15 direction, as described.
